George Donald Flait, Wyndmoor, Pa., assignor to
Proctor & Schwartz, Inc., Philadelphia, Pa., a cor-
poration of Pennsylvania

Filed Feb. 1, 1967, Ser. No. 5,654

Term of patent 14 years

(Cl. D55—1)

FIG. 1.

FIG. 2.

FIG. 3.

FIG. 1 is a side elevational view illustrating a novel slat of the present invention and showing in broken lines its combination with other slats into a spike apron;

FIG. 2 is an enlarged fragmentary perspective view of the slat shown in FIG. 1 showing in broken lines its connector element; and

FIG. 3 is an inverted plan with a portion broken away of the slat shown in FIG. 2.

The broken lines shown in the several views are for illustrative purposes only.

I claim:

The ornamental design for a slat for a spike apron, substantially as shown and described.
